DESIGN FOR A DOLL HEAD

Mary Hasell Lakopolanska, New York, N. Y.

Application November 9, 1939, Serial No. 88,153

Term of patent 3½ years

To all whom it may concern:

Be it known that I, Mary Hasell Lakopolanska, a citizen of the United States, residing at New York, in the county of New York and State of New York, have invented a new, original, and ornamental Design for Doll Heads, of which the following is a specification, reference being had to the accompanying drawing, forming part thereof.

In the drawing

Fig. 1 is a front view of a doll head, showing my new design; and

Fig. 2 is a side view thereof.

I claim:

The ornamental design for a doll head, as shown.

MARY HASELL LAKOPOLANSKA.
